UNITED STATES PATENT OFFICE.

KRAFT BOOTH, OF PHILADELPHIA, PENNSYLVANIA, ASSIGNOR TO GILLINDER & SONS, INC., OF PHILADELPHIA, PENNSYLVANIA, A CORPORATION OF PENNSYLVANIA.

DESIGN FOR AN ARTIFICIAL-LIGHT SHADE.

40,378.

Specification for Design.

Patented Nov. 30, 1909.

Application filed October 13, 1909. Serial No. 522,498. Term of patent 14 years.

To all whom it may concern:

Be it known that I, KRAFT BOOTH, a citizen of the United States, and resident of the city and county of Philadelphia and State of Pennsylvania, have invented a new, original, and ornamental Design for an Artificial-Light Shade, of which the following is a specification, reference being had to the accompanying drawing.

In said drawing the figure is a top or plan

view of an artificial light shade showing my design.

I claim—

The ornamental design for artificial light shade as shown.

KRAFT BOOTH.
